UNITED STATES PATENT OFFICE.

CHARLES S. LINCOLN, OF WAUWATOSA, WISCONSIN, ASSIGNOR TO ALLIS-CHALMERS MANUFACTURING COMPANY, OF MILWAUKEE, WISCONSIN, A CORPORATION OF DELAWARE.

PULVERIZER.

1,309,805.

Specification of Letters Patent. Patented July 15, 1919.

Application filed July 1, 1916. Serial No. 107,478.

To all whom it may concern:

Be it known that I, CHARLES S. LINCOLN, a citizen of the United States, residing at Wauwatosa, in the county of Milwaukee and 5 State of Wisconsin, have invented a certain new and useful Improvement in Pulverizers, of which the following is a specification.

This invention relates to improvements in the construction of crushing and pulverizing machinery, and particularly to improvements 10 in the construction of discharge grids or grates for impact pulverizers and the like.

An object of the invention is to provide a discharge grid or grate which is simple in 15 construction and efficient in operation.

One of the more specific objects is to provide a simple and efficient grate bar, which when excessively worn on one side, may be readily reversed and further utilized by exposing another side thereof to wear. Another specific object is to provide a spacing element for the grate bars of discharge grids, which is simple in construction and which will permit ready insertion, removal and 25 reversal of the bars. A further specific object is to provide other details of construction of grids or grates which will reduce the cost of construction and of maintenance to a minimum.

30 In applying this invention it is preferable to utilize standard rectangular sectioned bars of very hard material, such as tool steel, the bars being merely cut into suitable lengths by transverse sawing along a single plane, without reducing the cross section of the bars at any point throughout their lengths. The bars after being sawed into suitable lengths are provided with recesses adjacent their ends. While these recesses 35 have been disclosed as through openings, it is apparent that the same may take various other forms. Spacing elements which are preferably cast or otherwise formed in one piece and provided with integral projections 40 or lugs engageable with the recesses of the adjacent bars, are insertable between adjacent ends of successive bars and are constructed to permit ready reversal of the bars.

45 A clear conception of an embodiment of the invention may be had by referring to the drawing accompanying and forming a part of this specification in which like reference characters designate the same or similar parts in the various views.

50 Figure 1 is a transverse vertical section

through an impact pulverizer having the invention applied thereto.

Fig. 2 is an enlarged transverse vertical section through a fragment of the pulverizer grate, showing the same applied to a fragment of the pulverizer casing.

Fig. 3 is a side elevation of one of the spacing elements.

Fig. 4 is an end elevation of one of the spacing elements looking toward the retaining lugs thereof.

Fig. 5 is a fragmentary side elevation of one of the grate bars.

The pulverizer housing comprises a main casing 1 forming a pulverizing chamber 4 and provided with inlet and discharge passages or openings 5, 8, respectively. The main shaft 2 is rotatably mounted in suitable side bearings of the casing 1, and has secured thereto a rotor comprising a suspension element 3 and a series of revolvable beaters 7. The upper and side portions of the casing 1 adjacent the path of the beaters 7, are provided with suitable liners 9, while the lower portion of the casing 1 adjacent the discharge opening 8 is provided with a grid or grate comprising a series of grate bars 6.

The grate bars 6 are formed of standard bar section material of rectangular cross section, and are preferably cut square at the ends, as indicated in Fig. 5. The end portions of the bars 6 are provided with recesses formed as transverse through openings 12, and normally engage curved side recesses 13 in the casing 1. The bars 6 are also preferably formed of a suitable wear resisting material, such as tool steel, which is commercially obtainable at reasonable cost in rectangular sectioned bar form. Between adjacent ends of the successive grate bars 6 of the assembled grate, are placed spacing elements 10, having laterally projecting lugs 11 extending from one side thereof. These spacing elements 10 are formed of suitable thickness determined by the desired size of the product discharged from the pulverizer, and are formed wedge-shaped or tapered in order to position the grate bars 6 substantially radially, as indicated in Figs. 1 and 2. The spacing elements 10 are preferably formed out of any suitable material, by casting or drop forging, and require little or no finishing.

During the normal operation of the pul-

verizer the material to be reduced is admitted to the pulverizing chamber 4 through the inlet opening 5, being reduced by impact with the revolving hammers or beaters 7 and with the adjacent liners 9. When the material has been reduced sufficiently to permit passage thereof through the slots between successive grate bars 6 of the discharge grid, the reduced material is delivered from the pulverizer through the discharge opening 8.

When the bars 6 become worn along the edges thereof which are exposed to the pulverizing chamber, to such an extent that the uniformity of the discharged material is materially affected, the worn bars may be removed from the recesses 13 by removal of one or more of the liners 9 adjacent the end of the grate, and re-inserted in the recesses 13 in reverse position. The adjacent spacing elements 10 are formed to readily permit such reversal of the bars 6, by having the lugs 11 located equidistant from the ends thereof. The bars when so reversed again furnish suitable wearing surfaces and maintain the desired uniformity and size of the product delivered from the machine.

By utilizing rectangular section or other commercial form of bar tool steel for the construction of the bars, the cost of manufacture and of maintenance are reduced to a minimum. The reversibility of the bars extends the life thereof, thereby further reducing the cost of maintenance of the pulverizer. By maintaining the bars of uniform cross section throughout their length, bars of uniform strength are attained and the cost of manufacture is reduced to a minimum, as the construction of the bars is accomplished by sawing them from the bar stock. The formation of the recesses or holes 12 in the ends of the bars may be readily accomplished by drilling. These recesses provide simple and efficient means for retaining the spacing elements 10 in position.

The spacing elements 10 may be formed of any suitable material and require little or no finishing. By making the spacing elements 10 independent of the adjacent bars 6, these elements may be readily removed and new ones of different thickness inserted, in case it is desirable to vary the size of the product discharged. As the spacing elements are located entirely within the side recesses 13, they are not subjected to any con-

siderable wear and may therefore be used indefinitely, irrespective of renewal of the adjacent bars 6.

It should be understood that it is not desired to be limited to the exact details of construction shown and described, for obvious modifications will occur to a person skilled in the art.

It is claimed and desired to secure by Letters Patent—

1. As an article of manufacture, a spacing block for grate bars, having a pair of retaining lugs spaced equidistant from its opposite ends.

2. In combination, a series of grate bars each having a pair of recesses adjacent an end thereof, and a spacing element between adjacent ends of successive bars, said element having retaining lugs engageable with said recesses of either of said adjacent bars.

3. In combination, a rectangular sectioned grate bar having a pair of recesses adjacent an end, and a spacing block having lateral projections reversibly engageable in said recesses.

4. As an article of manufacture, a spacing block for grate bars, having a pair of retaining lugs projecting from one side thereof and spaced equidistant from its opposite ends.

5. As an article of manufacture, a tapered spacing block for grate bars, having a pair of retaining lugs spaced equidistant from its opposite ends in the direction of the taper.

6. In combination, a spacing element having a projection, and a pair of grate bars detachably directly engageable with opposite sides of said element, at least one of said bars being reversibly engageable with said element projection.

7. In combination, a spacing element having a projection formed integral therewith, and a pair of grate bars reversibly directly engageable with said element, at least one of said bars having a recess adapted to reversibly receive said element projection.

8. In combination, a series of grate bars each having a pair of spaced recesses adjacent an end thereof, and a spacing element between adjacent ends of successive bars, said element having retaining lugs engageable with said recesses.

In testimony whereof the signature of the inventor is affixed hereto.

CHARLES S. LINCOLN.
